REMOVAL OF WAX FROM HYDROCARBON OIL

Bernard Y. McCarty, Beacon, N. Y., and William E. Skelton, Cambridge, Mass., assignors to The Texas Company, New York, N. Y., a corporation of Delaware

No Drawing. Application November 30, 1931,
Serial No. 578,207

6 Claims. (Cl. 196—19)

This invention relates to the removal of wax from hydrocarbons and more particularly to an improved process for the removal of paraffin from lubricating oil fractions derived from petroleum.

The invention contemplates a process of dewaxing wax-containing lubricating oil fractions by filtration at low temperatures, wherein the wax-containing oil is mixed with a wax-precipitating liquid medium composed of a solvent liquid or mixture of solvent liquids which is completely miscible with, and exerts a substantially complete solvent action upon, the oil at the temperatures at which the wax constituents are precipitated from the oil in solid form and which has substantially no solvent action on the solid hydrocarbons at such temperatures. The resulting mixture is then chilled to precipitate the solid hydrocarbons which are removed by filtration.

More specifically the invention contemplates mixing with lubricating oil fractions a wax-precipitating liquid medium composed of a mixture of iso-propyl-ether and a liquid selected from the group comprising ethylene dichloride, propylene dichloride and methyl ethyl ketone.

An object of this invention is to effect dewaxing of paraffin-containing hydrocarbon oils with an improved type of solvent liquid composed of a mixture of solvents having selective solvent properties between the oil and the wax constituents and which, in addition, retains its selective solvent properties at relatively low temperatures whereby the precipitation of the wax from the mixture, particularly in the case of mixtures with relatively viscous oils, is effected in a more readily filterable form. At the same time, a high yield of dewaxed oil is obtained.

A further object has been to develop a solvent liquid which possessed the foregoing properties at relatively low temperatures and which is, therefore, adaptable for the manufacture of lubricating oils having pour tests of -20° F. and lower.

A selective solvent suitable for the foregoing dewaxing operation, and particularly when composed of two or more organic solvents, must retain its homogeneity and its property of remaining completely miscible with the liquid hydrocarbon constituents of the mineral oil at temperatures substantially well below 0° F. Complete miscibility is necessary in order to prevent separation of such liquid hydrocarbons from the solution. Such separated liquid hydrocarbons materially increase the viscosity of the solution thereby tending to reduce the filtering rate to a point where the operation is not economical. In addition, the presence of this separated liquid

gives rise to a condition which is productive upon filtration of a wax cake containing substantial amounts of oil so that the maximum yield of dewaxed oil is not realized.

It is essential that such a solvent mixture remain completely homogeneous at these low temperatures and not exhibit any tendency for any of its components to separate from the mixture. Upon separation of one of the components from the solvent mixture, the ratio of the components remaining in the mixture is altered, thereby changing its selective solvent properties so that the wax constituents will not be completely precipitated and/or appreciable amounts of the liquid hydrocarbon may separate from the solution due to the resulting lack of complete miscibility on the part of the solvent with the oil owing to its altered condition.

Extensive investigation has demonstrated that a solvent liquid or solvent mixture satisfactory for use as a wax-precipitating medium in the dewaxing of wax-containing hydrocarbon oils must possess, among other things, low absolute viscosity and low viscosity temperature coefficient, high oil solubility at low temperatures, low wax solubility at low temperatures, low freezing point, and also possess the property of precipitating wax in a readily filterable condition.

Accordingly, after investigating various solvent liquid mixtures, it had been found that a mixture of iso-propyl-ether and either ethylene dichloride, or propylene dichloride, or methyl ethyl ketone, possesses the foregoing combination of properties, thereby rendering it superior to the solvent liquids or liquid mixtures hitherto used in the art and, therefore, particularly well adapted as a wax-precipitating medium for use in the manufacture of low pour test paraffin base lubricating oil. The relative proportion of these liquids to each other, as well as that of the resulting solvent mixture to the oil, may be varied as desired, depending upon the nature of the oil undergoing treatment.

Thus when dewaxing the lubricating distillate fraction, having a viscosity of around 70 to 80 Saybolt Universal seconds or higher at 210° F., about thirty parts of the oil may be mixed with about seventy parts of a solvent mixture composed of around 70 to 80% of iso-propyl-ether and 30 to 20% propylene dichloride. The resulting mixture is then chilled to about -10° F. or to a temperature corresponding substantially to the desired pour test of the resulting dewaxed oil, following which it is subjected to filtration while still maintained in a cold condition to separate the precipitated wax constituents. Advanta-

geously filtration may be carried out in the presence of a comminuted filter aid material which may be added to and commingled with the mixture of oil, solvent and suspended wax crystals. 5 After removal of the solvent liquid from the filtrate, the resulting lubricating oil will have a pour test of 0° F. or lower.

Somewhat similar results may be obtained, on the other hand, by mixing the oil in about the 10 same proportion with a solvent mixture composed of about 50% of equal parts of iso-propyl-ether and ethylene dichloride. In the case of methyl ethyl ketone a solvent mixture composed of approximately 60% of iso-propyl ether and 15 40% of methyl ethyl ketone is advantageous.

While the use of the foregoing solvent liquid mixtures has been described in connection with a lubricating distillate fraction of relatively high viscosity, it is contemplated that mixtures of 20 these solvent liquids may be equally well employed with oils of various viscosity ranges. It is also contemplated that mixtures of these solvent liquids are not necessarily restricted to dewaxing distillate fractions but may also be used 25 in dewaxing various wax-bearing fractions of mineral oil.

Obviously many modifications and variations of the invention, as hereinbefore set forth, may be made without departing from the spirit and scope 30 thereof, and therefore only such limitations should be imposed as are indicated in the appended claims.

We claim:

1. The process of dewaxing wax-bearing mineral lubricating oil comprising mixing the oil 35 with a selective solvent mixture composed of iso-propyl ether and ethylene dichloride in such proportions that the mixture has a selective action as between wax and oil at temperatures of around 0° F. and below, chilling the mixture to 40 solidify the wax, separating the solidified wax, and recovering the solvent from the resulting dewaxed oil.

45 2. In the process of manufacturing low pour test lubricating oils from wax-bearing mineral oils substantially as described, the step comprising mixing with the oil a selective solvent liquid composed of iso-propyl-ether in admixture with ethylene dichloride in which the iso-propyl-ether

is at least equal in volume to the ethylene dichloride.

3. In the process of manufacturing low pour test lubricating oils from wax bearing mineral oils substantially as described, the step comprising 5 mixing with the oil a selective solvent liquid composed of iso-propyl-ether in admixture with propylene dichloride in which the iso-propyl-ether is at least equal in volume to the propylene dichloride.

10 4. The process of dewaxing wax-bearing mineral lubricating oil comprising mixing the oil with a selective solvent mixture composed of isopropyl ether and propylene dichloride in such proportions that the mixture has a selective action as 15 between wax and oil at temperatures of around 0° F. and below, chilling the mixture to solidify the wax, separating the solidified wax, and recovering the solvent from the resulting dewaxed oil.

20 5. The process of manufacturing lubricating oil having a pour test of 0° F. or lower from wax-bearing mineral oil which comprises mixing with the oil a selective solvent liquid composed of iso-propyl-ether and a liquid selected from the group 25 consisting of ethylene dichloride and propylene dichloride, the solvent liquid being mixed in such proportion that at temperatures of the order of -10° F., the mixture has substantially complete solvent action on the oil, and substantially no 30 solvent action on the wax, chilling the mixture to a temperature of about -10° F. or lower to precipitate the wax constituents as solid hydrocarbons, and removing the solid hydrocarbons so precipitated.

35 6. The process of dewaxing wax-bearing mineral lubricating oil comprising mixing the oil with a selective solvent mixture composed of iso-propyl ether and a liquid selected from the group consisting of propylene dichloride and ethylene 40 dichloride in such proportions that the mixture has substantially complete selective action as between wax and oil at temperatures of the order of -10° F., chilling the mixture to solidify the wax, filtering the cold mixture in the presence of 45 a filter-aid material to separate the wax, and recovering the solvent from the resulting dewaxed filtrate.

BERNARD Y. McCARTY.
